STRIP CUTTER

Jerome E. Cook, Larchmont, N. Y., assignor to
Bigelow-Sanford Carpet Co. Inc., Thompson-
ville, Conn., a corporation of Massachusetts

Application April 15, 1936, Serial No. 74,397

2 Claims. (Cl. 30—293)

This invention relates to cutters particularly of the type adapted for cutting strips from carpets and the like.

The cost of manufacture of assembled rugs constructed of strips of pile fabric joined with seams at abutting edges is excessive in comparison with the cost of weaving the fabric from which the rug is made, due to the relatively high costs of trimming, assembling, etc., and an object of the present invention is to reduce these latter costs by the provision of a simple cutting mechanism with which strips of carpeting, both straight and curved, can be cut from large areas rapidly and with precision. To that end my invention provides a cutting blade disposed at an adjustable predetermined distance from a gauge abutting the edge of the rug and supported on a carriage having a presser foot which rides over the surface of the rug and depresses the same against the draw-cutting action of the blade. As will appear, I preferably provide a pair of such presser feet, one adjacent the edge abutting gauge and the other spaced from it a distance somewhat greater than the width of the strip to be cut, with the blade interposed between the two presser feet and in approximate alignment therewith.

As a modified embodiment of my invention, I provide a cutter with gauge of novel construction adapted for measuring the width of cut on straight and curved strips interchangeably.

These and further objects and advantages of my invention will appear from a more detailed description thereof in connection with the accompanying drawings, in which—

Fig. 1 is a plan view of the preferred embodiment of my invention;

Fig. 2 is a side elevation view thereof;

Fig. 3 is a detail vertical section taken on the line 3—3 of Fig. 2;

Fig. 4 is a detail section taken on the line 4—4 of Fig. 2;

Fig. 5 is a detail perspective view of the blade supporting sleeve member;

Fig. 6 is a plan view of a modification;

Fig. 7 is an elevation view of the device of Fig. 6;

Fig. 8 is a perspective unassembled view of the blade securing means for the modified embodiment; and

Fig. 9 is a perspective view illustrating the manner of use of either embodiment of my cutter.

Referring to Figs. 1 and 2, the carriage of the cutter therein illustrated comprises a gauge plate 1 connected by a rod 3 extending perpendicular

to the rug engaging surface of the gauge plate and also by a cross bar 4, with a presser foot 2, which may be arcuate in its rug contacting surface, as indicated in Figs. 2 and 9. The rod 3 has reduced screw threaded ends 5 and 6, one of which passes through the gauge plate 1 and is secured by the nut 10 and the other of which passes through the presser foot 2 and is secured by the nut 11. The cross bar 4 may have a flange 12 at one end drilled to receive the reduced end 6 of the rod 3 and to be secured upon tightening of the nut 11 by abutment of the adjacent shoulder on the rod 3 and at its other end may have a flange 14 secured to the gauge 1 by a suitable bolt or rivet 15.

A second presser foot in the form of a flanged plate 20 is preferably secured to the gauge 1, as by screws 21, at a sufficient distance above the lower surface of the gauge to leave a rug edge abutting surface on the gauge as indicated in Fig. 3.

Slidably mounted on the rod 3 is a sleeve member 25, the details of which are illustrated in Fig. 5, which has a centrally disposed bore 26 to receive the rod 3 and which is provided with parallel spaced arms 30. The blade holder 35 is pivoted between the arms 30 by a pivot 36 passing through the apertures 32 in arms 30 in alignment with an aperture extending through the holder 35. The holder may conveniently be hollow to receive spare blades 38 and the end is closed by a screw threaded plug 39.

The blade 40, which may be a razor blade of common type having a central elongated aperture 41 (Fig. 2) is secured between the end 42 of the holder and a plate 43 having lugs 45 (Fig. 4) of a shape and size to be received by the slot 41 of the blade to secure the blade against turning in the holder. A bolt 52 with wing nut 53 secures the parts together.

The width of the strip being cut is indicated by graduations on a flattened surface 60 of the rod 3 and the edge 61 of the sleeve member 25 may effectively act as a cross-bar co-operating with the scale to indicate the reading. Obviously, the distance between the edge 61 and the cutting blade 40 should be compensated for by commencing the scale graduations with the appropriate number at the gauge 1. The sleeve member 25 is moved along the rod 3 until the desired width is indicated and the sleeve is secured in this position by a thumb bolt 65 passing through the flat portion 60 of the sleeve and abutting the flat portion 60 of the rod 3, as indicated in Fig. 2.

To aid in propelling the device over the sur-

face of the rug, which is inverted for cutting as indicated at A in Fig. 9, a second handle 70 is secured to the gauge 1.

For cutting strips of narrower widths than those for which the cutter just described is usually employed, or for cutting strips having curved edges, I have indicated as a modification in Figs. 6-8, a device in which the gauge plate, instead of being formed with a continuous surface as in the gauge plate 1, comprises a strip of sheet metal 101 cut away at 104 and bent inwardly at 120 to form the presser foot. The depending strips 107a and 107b on both sides of the cut away portion are bent into semi-circular form to provide companion gauge members. The rod 103 is secured perpendicular to the upstanding portion of the strip 101 by the nut 110 and lock nut 111 and has a wheel 102 mounted on a bearing 80 suitably secured to its opposite end. In this embodiment the cross member 4 of the carriage is omitted.

As a modification of the manner of adjustably mounting the blade holder 135 on the rod 103, I dispense with the sleeve 25 of the other embodiment and pass the rod 103 directly through the aperture 146 (Fig. 8) in the extension 142 of the blade holder 135, aperture 147 in plate 143 and aperture 141 in the blade 140. For a purpose which will appear, in this embodiment I eliminate the pivotal mounting of the blade holder 135 relative to the rod 103 and rigidly secure the blade holder to dispose the blade 140 at a predetermined angle relative to the surface of the rug A' to be cut, as indicated in Fig. 7. For this purpose the rod 103 is provided with oppositely disposed flat surfaces 160 and 161 and the aperture 146 through the holder extension 142 has correspondingly flattened opposite surfaces, as indicated in Fig. 8. To change the inclination of the angle of the blade 140 the nut and lock nut 110 and 111 are loosened to permit rotation of the rod 103 to the position necessary for the desired inclination.

In this embodiment, I have adopted a different means for clamping together the plate 143 and extension 142 between which the blade 140 is secured. In this instance a screw thread 200 is formed on the round surfaces of the rod 103 and a knurled nut 201 and knurled nut 202 with collar 203 are threaded onto the rod 103 on opposite sides of the blade holder to secure the blade and holder. Adjustment of the blade 140 along the rod 103 for different widths of the strip to be cut, as indicated by the scale, may be effected by backing off and tightening the nuts 201 and 202.

In using my modified embodiment to cut narrow straight strips from the edge of a rug, the

rug is placed tangentially of the semi-circular guide members 107a and 107b and an accurate cut is obtained. When the cutter is used to cut a convex curved strip, such as is indicated at A', the open portion 104 between the semi-circular gauge members 107a and 107b permits the curved rug edge to protrude between the gauge members and the semi-circular formation of the gauge members permits them to follow the curved outer edge of the rug in an obvious manner to make a cut such as indicated at B'. Similarly, the gauge members 107a and 107b are effective for cutting strips from carpeting having a concave edge such as indicated at A''.

It is primarily for the purpose of assuring accuracy in making such curved cuts that I secure the blade edge at a predetermined angle relative to the surface of the rug in this embodiment of my cutter.

In making a concave cut, if the tip end of the blade be adjusted at an angle such that the cut commences at a point about opposite the gauge member 107a, the scale 103 will indicate with sufficient accuracy the width of the curved strip to be cut whether it be convex curved as at A' or concave as at A''.

I claim:

1. In a rug strip cutter, the combination of a gauge adapted to abut the edge of the rug to be cut, a presser member adjacent the gauge adapted to bear on the upper surface of the rug adjacent the said edge, a second presser member, means connecting the two presser members to space the second presser member a predetermined distance from the first presser member, a blade holder and means for mounting the blade holder on said connecting means intermediate said presser members, the said blade holder being pivotally mounted to afford a free swinging movement of the blade toward and away from the work as the cut progresses.

2. In a rug strip cutter for cutting curved strips, the combination of a plurality of gauge members adapted to abut the edge of the rug to be cut and spaced from each other to allow protrusion, between the gauge members, of curved rug edges, a presser member remote from said gauge members, means connecting the presser member and the gauge members, a blade holder, means for mounting the blade holder on said connecting means intermediate said presser member and said gauge members, and means for adjustably fixing the inclination of the blade holder relative to the surface of the work, whereby to gauge the depth of cut.

JEROME E. COOK.
